UNITED STATES PATENT OFFICE.

HENRY W. EASTMAN, OF BALTIMORE, MARYLAND.

VENTILATING-DOOR.

SPECIFICATION forming part of Letters Patent No. 295,989, dated April 1, 1884.

Application filed September 10, 1883. (No model.)

To all whom it may concern:

Be it known that I, HENRY W. EASTMAN, of the city of Baltimore, and State of Maryland, have invented certain Improvements in 5 Ventilating-Doors, of which the following is a specification.

This invention relates to an improved door for sleeping-chambers and other apartments, whereby ventilation may be had without destroying the privacy of the chamber or admitting thereto mosquitoes, flies, and other insects.

The said invention consists in providing a door with a slatted aperture, over which is placed a screen of wire-work or other material 15 which will admit of the free passage of air to and from the chamber, but at the same time intercept flies and mosquitoes, and one or more imperforate doors to cover the screen and thoroughly close the opening, as will herein- 20 after fully appear.

In the accompanying drawings, forming a part hereof, Figure I is a vertical section of the improved door. Fig. II is a view of the outside of the door. Fig. III is a view of the 25 inside of the door, or as it appears from the chamber, and with one of the imperforate doors open. Figs. IV, V, VI, and VII illustrate modifications in the construction of the slats, as hereinafter described.

30 Similar letters of reference indicate similar parts in all the views.

A is the chamber-door having an opening through it, which is here shown as of a size corresponding to the two upper panels and 35 the bar between them.

B B are fixed slats, arranged to give free 40 passage for air to and from the apartment without destroying its privacy. Where the door A opens on a corridor or public passage the slats B may be of the ordinary inclined description, which prevents inspection of any- 45 thing within the apartment, but allows persons within the chamber to distinguish objects in the corridor or passage; but as this door is

designed in many cases as a communicating 45 one between two chambers, the privacy of both has to be maintained. I therefore employ slats with a double incline, as shown in the various figures of the drawings. In Figs. I, II, and III the slats are represented as formed 50 of sheet metal with flat sides and the edges wired. In Fig. IV curved metallic slats are shown, while those in Figs. V and VI are made of wood and without the wired edge. In Fig. VII the slats are of sheet metal and their 55 rigidity increased by means of flanges *a* instead of wires.

C is a screen of fine-wire work placed over the inner edge of the slats B, to prevent entrance to the room of insects.

D D are folding imperforate doors, made to represent ordinary panels hinged within the aperture of the door, and adapted to be closed on or against the wire screen C.

It will be understood that when the imperforate doors D D are open there is free access 65 of air to and from the apartment, but the privacy of the chamber is not destroyed or insects admitted thereto.

In applying this invention to doors now in 70 use the upper panels and the bar between them are removed, and the slats, screen, and imperforate doors substituted for them.

I claim as my invention—

1. A ventilating-door having a slatted opening, and one or more imperforate doors adapted 75 to close the said opening, substantially as specified.

2. A ventilating-door having a slatted opening covered with a screen, and one or more 80 imperforate doors adapted to close the said opening, all combined substantially as specified.

HENRY W. EASTMAN.

Witnesses:

WM. T. HOWARD,
RENOUX REESE.
